UNITED STATES PATENT OFFICE.

HENRY M. CASE, OF CINCINNATI, OHIO, ASSIGNOR TO THE CINCINNATI STAMPING COMPANY, OF CINCINNATI, OHIO, A CORPORATION OF OHIO.

VENTILATOR.

1,412,607.

Specification of Letters Patent. Patented Apr. 11, 1922.

Application filed January 18, 1919. Serial No. 271,789.

To all whom it may concern:

Be it known that I, HENRY M. CASE, a citizen of the United States, and a resident of Cincinnati, in the county of Hamilton and State of Ohio, have invented certain new and useful Improvements in Ventilators, of which the following is a specification.

My invention relates to ventilating apparatus, and its object is to provide a ventilator to be placed in the lower part of a window under the raised lower sash so that this ventilator can be readily adjusted to windows of different widths and may also be readily adjusted to admit a greater or less amount of air. A further object is to permit of use of the ventilator in windows having the lower sashes of various thicknesses so that the ventilator will remain in place without rattling.

My invention consists in the combination of parts and in the details of construction and arrangement of parts as will herein-after be more fully described and claimed.

In the drawing:

Fig. 1 is a perspective view of part of a window showing my improved ventilator installed therein;

Fig. 2 is an outside or rear elevation of the same;

Fig. 3 is a vertical cross-section on a plane corresponding to the line 3—3 of Fig. 2;

Fig. 4 is a horizontal cross-section on a plane corresponding to the line 4—4 of Fig. 1; and

Fig. 5 is a detail perspective view of one of the end adjusting plates.

As I prefer to construct my invention, it comprises the main plate 1 and the extensible plate 2. These plates stand upright with the plate 2 behind or outside the plate 1; said plate 2 having along its lower edge the forwardly extended flange 3 which has along its front edge the upturned rib 4 throughout the length of the plate 2. At the top, the plate 2 has the forwardly extended flange 5 with the upwardly extended rib 6 along the front edge thereof. The left-hand end of the plate 2 from its upper flange 5 to its lower flange 3 is merely reinforced by a hem or bead 7 turned back on the outside thereof.

The main plate 1 is of general formation similar to the plate 2 just described; hav-

ing the lower forwardly extended flange 8 with upturned front rib 9 lying above and inside the flange 3 and rib 4 of the plate 2. And at the top the plate 1 has the forwardly extended flange 10 lying under the flange 5 of the plate 2; and extending up in front of the rib 6 of this upper flange 5, and turned back thereover and down therebehind is the hooked rib 11. The plate 2 is thus held to slide longitudinally behind the main plate 1. The right-hand end of the main plate 1 has a bead 12 turned over on its front side and is further reinforced by a rib or brace 13 running from the upper flange 10 to the lower flange 8 to which its respective ends are attached, and having a flange 14 fitting under the bead 12. These parts are preferably attached together by solder.

The left-hand end of the plate 1 and the right-hand end of the plate 2 are stiffened and made to have sufficient front-to-rear width to bear properly against the window casing by attaching thereto end pieces 15 of V-shaped cross-section; one leg 16 of the V running at right angles to the respective plate 1 or 2, and having along its rear edge an S-shaped crimp 17 (Fig. 4) with its rearmost fold opening toward the respective end of the plate 1 or 2 and receiving said end in said fold; this crimp being tightly compressed and the parts being soldered together. The other leg 18 of the V extends at approximately forty-five degrees to the plate 1 or 2 from its junction with the forward edge of the part 16 and has its rear edge soldered to the front side of the respective plate 1 or 2. The top and bottom ends of the part 16 of each end piece 15 are attached to the forwardly extended flanges 5 and 3 or 10 and 8, as the case may be; this being accomplished by turning up short lugs 19 on the ends of the respective flanges, which lugs lie inside the parts 16 and are soldered thereto. By this construction, the ends of the device are made very substantial.

As I prefer to make the device, these ends are about an inch wide. But the lower sashes of windows vary in thickness from about the width of these ends up to two or three inches. Therefore, the space between the stops that guide the sash would often be too wide for my ventilator to be effectively supported in upright position at the ends

- as it should be by fitting rather snugly between the inner and outer stop of the window. If it does not make effective contact at the end, there is a tendency for it to rattle under disturbances, as, for instance, when the wind is blowing. I provide for adjusting my ventilator to these spaces by providing an end adjusting plate 20 which, as I prefer to make it, is of angular cross-section 5 having a wider member 21 and a narrower member 22; the former being adapted to lie up along the outer surface of the part 16 at the end of the ventilator and the narrower member 22 lying outside or to the rear and 10 extending in across the rear side of the ventilator a short distance. This plate is attached to the ventilator end, as here shown, by means of a bolt 23 passing through a slot 24 in the member 21 of the plate 20 and passing in 15 through the end-piece 15 and through a slight boss 25 formed in the inner leg 18 of the V-shaped end piece 15 where the bolt receives a wing nut 26. Preferably the slot 24 opens through the front edge of the member 21 so 20 that the adjusting plate may be readily slipped on or off of the bolt 23, thus obviating the complete removal of the bolt in order to attach the adjusting plate. The inturned rear member 22 which, as here shown, is preferably doubled upon itself to reinforce the entire adjusting plate, in addition to thus providing the reinforcement affords a more extended surface to bear against the inner or front side of the outer or rear window stop 25 27 (Fig. 4) while the front edge of the ventilator end 15 bears against the rear side of the inner or front stop 28.
- The left-hand end part of the main plate 1 is provided with a plurality of perforations 29, these being, as I prefer to make the ventilator, about five-eights inch in diameter and spaced about one inch from center to center; this arrangement of perforations occupying about half the area of the main plate 1 and beginning a short distance from the left-hand end. It is manifest, however, that the size and spacing of these perforations may be varied as well as may be the extent of the perforated part of the plate. 40
- With the extensible plate 2 of about the same length as the main plate, these perforations will, of course, be covered by the plate 2 when the ventilator is adjusted to its shortest condition. This completely closed condition is desirable for packing and storing the ventilators; it is seldom that a window would be provided with a ventilator and require the ventilator to be so short. As the ventilator is extended to fit windows of usual widths, the perforations 29 in additional numbers will be uncovered. Therefore, the extension of the ventilator to fit windows automatically provides additional ventilating area somewhat in proportion to the size 45 of the window. This is desirable since a

very narrow window usually opens into a comparatively small room which would require not so much area of ventilating inlet; whereas the larger window, which is generally found in a larger room, should be 70 provided with a ventilator having much greater inlet area for the ventilation of such larger room.

If the air is permitted to pass directly into the room through the perforations 29, 75 it causes drafts which are injurious to the occupants of the room; and also there is generally an objectionable amount of dust, soot and other impurities deposited in the room by such directly entering air. Fine mesh 80 screens placed in the ventilating openings guard against these objectionable results to a certain extent, but they largely nullify the ventilating effect which the devices of that kind are designed to produce. Also such directly opening ventilating inlets will admit 85 the rain, especially when blown by the wind; whether the opening be screened or not.

I obviate these disadvantages without objectionably minimizing the desired ventilating effect by providing across the front of the main plate 1 throughout the area that has the perforations 29 the inverted chute 30 which comprises the front part 31 attached to the plate 1 just above the lower 90 flange 8 thereof, and extending upwardly and inclining inwardly away from said plate 1 at an angle of between thirty and forty-five degrees, preferably; and the side parts 32 joining the front part 31 along its lateral 95 edges and preferably being integral therewith and extending the full height thereof and extending back with horizontal top edges, and being fastened to the front of the plate 1 at the lateral terminations of the 100 area having the perforations 29. The attachment of these parts 31 and 32 to the plate 1 is preferably effected by turning out narrow flanges 33 and 34, respectively, 105 which are soldered to the front surface of 110 the plate 1.

This chute, thus opening upwardly and with its inclined front part 31, deflects the air currents entering through the perforations 29 upwardly where they will not directly contact with the occupants of the room, but will spread gradually throughout the upper part of the room and descend in less concentrated form to properly modify the temperature and increase the purity of 115 the atmosphere of the room. Also, dust, soot or rain entering through the perforations 29 and striking the sides of the chute 30 will be retarded and their distribution throughout the room will be largely prevented. 120

As before stated, the maximum capacity of the ventilator is determined automatically by the same means that effect the adjustment of the ventilator to the window of a given width. But the amount of ventilation de- 125 130

sired at different times through the same window will, of course, vary. The colder the weather, the less area of ventilating opening is needed. I provide for this variation by means of a sliding lid 35 on the top of the chute 31. As here shown, this lid is made to slide forwardly and backwardly on the top of the chute; closing the top of the chute entirely and thus cutting off all ventilation when it is pushed entirely back with its rear edge against the front of the plate 1. The farther forward this lid is pulled, the more of the top of the chute 31 is opened and the greater the conducting capacity of the chute for the air coming in through the perforations 29. I prefer to mount this lid 35 to slide in this manner by providing the upper edges of the chute sides 31 and 32 with outwardly extended flanges 36 and 37, respectively, and providing the lid 35 with downwardly and inwardly turned flanges 38 and 39 that hook under the flanges 36 and 37, respectively; the front flange 38 of the lid 35, of course, disengaging from the front flange 36 of the chute as the lid is pulled forward, but the end flanges maintaining engagement and guiding the lid in its forward and backward movement.

The direct passage of the air, and of any impurities such as just mentioned, into the room is further discouraged by a longitudinal forwardly and downwardly inclined baffle 40 joining the main plate 1 at the top of the chute and extending about half way across the chute forwardly but preferably extending the full length of the chute. This tends to cause the air currents to more directly strike the inclined front 31 of the chute and thereby be retarded and caused to drop most of their dust, soot, moisture and other objectionable matter.

The lowermost part of the front 31 of the chute preferably lies above the lower edges of the lowermost row of perforations 29. In this way any water that enters the chute, as in the manner before alluded to, will readily drain therefrom onto the outer window sill. This likewise serves as an outlet for dust, soot and the like which may be collected in the chute and thus prevented from circulating through the room.

The ventilator thus constructed is installed for use by raising the lower sash, inserting the ventilator in the space thus left in the lower part of the window with the chute 30 extending into the room. The end plates 20 should be adjusted on the ends of the ventilator so that the ventilator will fit snugly between the sash stops at both ends; and then the ventilator is extended by drawing the plate 2 out from the plate 1, so that these ends fit snugly against the window casing surfaces between the stops at the opposite sides. Thus the ventilator is securely held in upright position by the window cas-

ing and its stops. The sash is then lowered onto the top of the ventilator, upon which the upwardly extended ribs 6 and 11 of the plates 1 and 2 will lie against the front surface of the sash along near the lower edge 70 thereof, as clearly seen in Fig. 1. These flanges thus extending up serve to prevent any direct entrance of air between the ventilator and the sash. The lower part of the ventilator, of course, comes down behind 75 the window sill, the same as with the sash if it were entirely down. Then all that is necessary to make the ventilator ready for use is to pull the lid 35 forward such distance as may be required in view of the 80 weather conditions. Thus installed, the ventilator will remain firmly in position under all conditions of wind pressure and will not be shaken nor damaged, and will cause no noise. At the same time, it is readily removed from the window for cleaning the ventilator or the window by merely drawing its plates 1 and 2 together slightly without disturbing any of the other adjustments. The flanged and ribbed construction of the 90 plates 1 and 2 in conjunction with providing ample bearing surfaces against the window parts and serving to overlap the lower edge of the sash as just described, afford very strong reinforcement of the edges and ends 95 of the ventilator so that the ventilator may be very strong and substantial though constructed of a comparatively thin sheet metal or other comparatively thin or weak material.

While certain constructional details are deemed preferable in connection with my invention, and I have shown and described these rather specifically in elucidating the construction and use of my invention, as is 105 required, I do not wish to be understood as being limited to such precise showing and description, but having thus fully described my invention, what I claim as new and desire to secure by Letters Patent is: 110

1. In a ventilator of sheet metal construction, an exterior vertical outer perforated wall, a tapered chute, of gradually increasing dimensions from bottom to top, mounted on the interior of said perforated wall 115 and extending upwardly with its interior opening in its top, a baffle plate in said chute extending from near the top of said vertical wall downwardly and inwardly partly across the opening through said chute to prevent a 120 draft and discharge of the elements from the outside, and a horizontal slidable lid mounted on the top of said opening and adapted to be moved thereacross toward and from said vertical wall to regulate the admission 125 of air therethrough, substantially as set forth and for the purposes specified.

2. In a ventilator, a plurality of plates 130 slidable longitudinally upon each other, one of said plates comprising ventilating means,

- 4
- and said plates being adapted to be inserted in a window in the space normally occupied by the sash, and to have its end parts come between the inner and outer stops of the window at the respective sides, and adjusting plates adjustably mounted on the opposite end parts of said members for adjustment across said end parts to fill the spaces between said stops, for the purposes set forth.
5. In a ventilator, the combination of two plates, each having forwardly extended top and bottom flanges and the bottom flanges having upwardly extended beads, the flanges and bead of one of said plates lying within the flanges and bead of the other plate, and the upper flange of said one of said plates having an upwardly and backwardly and downwardly extended hooked flange hooking over the upwardly extended bead of the upper flange of the other plate, whereby said plates are slideable upon each other, one of said plates comprising ventilating means.
6. In a ventilator, the combination of two plates, each having forwardly extended top and bottom flanges and the bottom flanges having upwardly extended beads, the flanges and bead of one of said plates lying within the flanges and bead of the other plate, and the upper flange of one of said plates having an upwardly and backwardly and downwardly extended hooked flange hooking over the upwardly extended bead of the upper flange of the other plate, whereby said plates are slideable upon each other, one of said plates comprising ventilating means.
3. In a ventilator, an upright plate, and an upright end piece having two members disposed so that it is of substantially V-shaped cross-section, one member of said end piece having a crimp along its free edge of substantially S-shaped cross-section receiving the end of said plate in one of the folds of said crimp, and the other member of said end piece inclining back against the adjacent surface of the plate and being secured thereto.
4. In a ventilator, an upright plate, an upright end piece having two members disposed so that it is of substantially V-shaped cross-section, one member of said end piece having a crimp along its free edge of substantially S-shaped cross-section receiving the end of said plate in one of the folds of said crimp, and the other member of said end piece inclining back against the adjacent surface of the plate and being secured thereto, an adjusting plate lying against the outer surface of said member that has the crimp, and having a transverse slot, and a bolt passing through said slot and through both members of said end piece, and clamping means on said bolt adjacent to said inclined part of said end piece, said adjusting plate being adapted to be adjusted transversely of said end of said plate, for the purposes set forth.
5. In a ventilator, the combination of two plates, each having forwardly extended top and bottom flanges and the bottom flanges having upwardly extended beads, the flanges and bead of one of said plates lying within the flanges and bead of the other plate, and the upper flange of said one of said plates having an upwardly and backwardly and downwardly extended hooked flange hooking over the upwardly extended bead of the upper flange of the other plate, whereby said plates are slideable upon each other, one of said plates comprising ventilating means.
6. In a ventilator, the combination of two plates, each having forwardly extended top and bottom flanges and the bottom flanges having upwardly extended beads, the flanges and bead of one of said plates lying within the flanges and bead of the other plate, and the upper flange of one of said plates having an upwardly and backwardly and downwardly extended hooked flange hooking over the upwardly extended bead of the upper flange of the other plate, whereby said plates are slideable upon each other, one of said plates comprising ventilating means.
